Primary Examiner — Vy N Koenig(57) **CLAIM**

The ornamental design for a camera mount, as shown and described.

DESCRIPTION

FIG. 1 is a right-side view of a camera mount, showing our new design;

FIG. 2 is a front view of the camera mount illustrated in FIG. 1;

FIG. 3 is a left-side view of the camera mount illustrated in FIG. 1;

FIG. 4 is a rear view of the camera mount illustrated in FIG. 1;

FIG. 5 is a bottom view of the camera mount illustrated in FIG. 1;

FIG. 6 is a top view of the camera mount illustrated in FIG. 1; and,

FIG. 7 is a perspective view of the camera mount illustrated in FIG. 1.

Broken lines are directed to environment only and form no part of the claimed design.
